UNITED STATES PATENT OFFICE.

GEORGE STEIN, OF NEW YORK, N. Y.

ELECTRIC LAMP.

SPECIFICATION forming part of Letters Patent No. 729,906, dated June 2, 1903.

Application filed August 12, 1902. Serial No. 119,420. (No model.)

To all whom it may concern:

Be it known that I, GEORGE STEIN, a citizen of the United States, and a resident of the city of New York, borough of Manhattan, in the county and State of New York, have invented a new and Improved Electric Lamp, of which the following is a full, clear, and exact description.

This invention relates particularly to improvements in small electric lamps designed for the use of physicians, surgeons, dentists, or the like in making nasal, mouth, and other examinations, the object being to provide a lamp so constructed that either a continuous or intermittent light may be had.

I will describe an electric lamp embodying my invention and then point out the novel features in the appended claims.

Reference is to be had to the accompanying drawings, forming a part of this specification, in which similar characters of reference indicate corresponding parts in all the figures.

Figure 1 is a perspective view of an electric lamp embodying my invention and showing its battery connections. Figs. 2 and 3 are longitudinal sections showing the parts of the lamp in different positions; and Fig. 4 is a perspective view showing in full lines the position of parts for intermittent lighting and indicating in dotted lines the position of parts for a continuous light.

The lamp comprises two tubular metal sections 1, 2. In one end of the section 1 the lamp 3 is arranged, having one pole of its filament in electrical connection with the section. The other pole of the filament is connected to a pin 4, adapted to be removably inserted in a tube 5, arranged in the tube-section 1, but insulated therefrom at one end by a block 6 of insulating material and at the other end by a block 7, of insulating material, the end of this block 7 being extended beyond the end of the section 1, so as to be inserted into the end of the section 2, thereby making use of the block 7 as a circuit-breaker. Arranged in the section 2 is a metal pin or rod 8, supported and insulated in the section by the blocks 9 and 10. The end of this pin or rod 8 is designed to removably engage in the tube 5.

From a battery 11, arranged in the case 12, a wire 13 extends to the rod 8, and a wire 14 is in electrical connection with the section 2 of the lamp.

Of course when not in use the two sections of the lamp may be separated and held in the straps shown on the casing. On one of the sections of the lamp, here shown as the section 1, is a spring-plate 15, designed to be pressed into engagement with the section 2 to close the circuit.

In operation when the adjacent ends of the sections 1 and 2 are slightly separated, as indicated in Fig. 2, the plate 15 when pressed against the section 2 will close the circuit, and of course upon releasing the pressure on said plate the circuit will be opened. Should a continuous light be desired—that is, a light for several minutes—the two sections 1 and 2 are moved together, as indicated in Fig. 3, thus closing the circuit.

Having thus described my invention, I claim as new and desire to secure by Letters Patent—

1. An electric lamp, comprising two tubular metal sections, a lamp removably placed in one of the sections, a metal tube in the section in which the lamp is arranged, a pin extended from one pole of the lamp-filament into said tube, a pin or rod arranged in the other section and adapted to removably engage in said tube, and electrical connections with said rod and with the section containing the lamp.

2. An electric lamp, comprising two tubular sections, a lamp removably supported in one of the sections, a tube in the lamp-supporting section, blocks of insulating material arranged in said section and supporting the tube, one of said blocks being extended beyond the end of the section so as to enter the other section, a pin having connection with the lamp-filament and extended into said tube, a pin supported in the other section and insulated therefrom and adapted to enter said tube, a battery, wires extended from said battery to connection with the rod and lamp section, and a circuit-closer arranged on one of the sections and adapted to be pressed into engagement with the other section.

In testimony whereof I have signed my name to this specification in the presence of two subscribing witnesses.

GEORGE STEIN.
